UNITED STATES PATENT OFFICE.

WALTER J. SPENCER, OF IVANHOE, MINNESOTA.

SWINGLETREE-HOOK.

1,256,946.

Specification of Letters Patent. Patented Feb. 19, 1918.

Application filed August 9, 1917. Serial No. 185,340.

To all whom it may concern:

Be it known that I, WALTER J. SPENCER, a citizen of the United States, residing at Ivanhoe, in the county of Lincoln and State 5 of Minnesota, have invented certain new and useful Improvements in Swingletree-Hooks, of which the following is a specification.

This invention relates to an improvement 10 in swingletree hooks; and it is a purpose to provide a hook of this character having parts associated therewith by which the traces are held against accidental or casual displacement.

15 A further object resides in so constructing the means associated with the hook, that very little interference is offered to the fitting of the traces upon the hook, and yet when the retaining mechanism moves into 20 place it is locked against being bent or distorted in such a way that the trace would be disconnected, through ordinary uses.

Yet another object is to construct the trace retaining member of a spring material 25 so that as the trace is fitted to the hook, this retaining portion will spring back in place and will hold in this position until again manually released.

With the above and other objects in view, 30 which will be in part described and in part understood from the specification, drawings, and claims, my invention consists in certain novel features of construction and combination of parts which will be hereinafter 35 more fully set forth.

In the drawings:—

Figure 1 is a view in elevation of a swingletree hook constructed after the manner of my invention;

40 Fig. 2 is an elevational view taken at an angle to the disclosure in Fig. 1; and,

Fig. 3 is a view in elevation showing a slightly modified form of retaining member.

45 The ferrule or ring 1 is adapted to be fitted and secured upon the end of the swingletree 2, in any desired and approved way, and the hook 3 is formed integral with or connected to this ferrule or ring 1, so 50 that when the member 1 is fitted upon the end of the swingletree the hook is disposed in the proper relation to be fitted through the eye 4 of the trace 5.

55 The parts as above set forth can be to all intents and purposes of substantial standard forms and designs, except that on the inner

side of the bill of the hook 3, an extension or lug 6 is provided. A retaining member 7, which is of spring material, is connected with the hook 3 and has the free end 8 thereof disposed to fit across the opening of the hook and bear on the inner side of the lug 6, substantially as is shown in Fig. 2, so that when the trace 5 is fitted upon the hook and this retaining member 7 65 springs against the lug 6, the retaining member will be disposed to guard against accidental or casual displacement of the trace from the hook, and at the same time this retaining member will be held by the 70 lug 6 against being bent through strain placed thereon.

In the present instance I have shown the retaining member as made from a length of spring wire which is looped about the 75 body portion of the hook 3 and is then extended to be looped and secured around the ferrule or ring 1, as indicated at 9.

As is shown in Fig. 3, the retaining member 10 is looped about the body of the hook 80 3, as shown at 11, and the end of this retaining member is passed through a lug or enlargement 12 on the ferrule or ring 1. While either of these manners of fitting the retaining member might be resorted to, and in 85 these adaptations it would be preferable that spring wire be used, ribbon metal might be employed, and the securement of the retaining member might be accomplished in other ways than disclosed. 90

From the foregoing it is seen that I have provided a swingletree hook which is of substantially standard form in its construction and design, and which has associated with the standard parts thereof, a retaining member so mounted and disposed that this member is very readily pressed aside to permit fitting of a leather, chain, or other form of trace, and which retaining portion will through its own resiliency spring back 100 in place to close across the opening of the hook to thus guard against accidental or casual displacement of the trace from the fitted and connected relation.

While I have in the foregoing description set forth only certain forms and constructions of the parts and have only hinted other changes, it will be of course understood that variations and mechanical assignments might be resorted to without departing from the spirit and scope of my invention, in view of which fact I wish to be

limited only to such points as may be set forth in the claims.

I claim:—

1. A swingletree hook including hook and mounting portions, said hook being provided with an enlargement on the bill thereof, and a resilient retaining member mounted in conjunction with the body of the hook and having a portion thereof extended to resiliently engage with the enlargement to close across the hook, the form and location of the enlargement being such that the resilient retaining member is braced against being casually moved from the retaining position.

2. A swingletree hook including hook and mounting portions, the bill of said hook being provided with an enlargement, and a retaining member connected at one of its ends in rigid mounting looped about the

body of the hook and having the free end thereof extended to close across the hook and to engage with the enlargement.

3. A swingletree hook including a ferrule or ring having a trace hook associated therewith, said hook having an enlargement on the bill thereof notched on its inner side, and a retaining member of resilient metal coiled about the body of the hook anchored at one of its ends in rigid mounting and having the remaining end extending across the opening between the body and the bill of the hook and engaging normally in the notch of the enlargement.

In testimony whereof I affix my signature in presence of two witnesses.

WALTER J. SPENCER.
